Application July 28, 1949, Serial No. 4,186

Term of patent 3½ years

(Cl. D33—8)

To all whom it may concern:

Be it known that we, Bernard G. Witz and Herbert Chaskin, citizens of the United States of America, and residing in Brooklyn, county of Kings and State of New York, have invented a new, original, and ornamental Design for a Kiddie Rack, of which the following is a specification, reference being had to the accompanying drawing, forming part thereof.

We claim:

The ornamental design for a kiddie rack, as shown.

BERNARD G. WITZ,
HERBERT CHASKIN.
